UNITED STATES PATENT OFFICE.

ANDREW G. BRANDT, OF SCRANTON, PENNSYLVANIA.

MILK-BOTTLE.

1,067,237.

Specification of Letters Patent.

Patented July 15, 1913.

Application filed July 23, 1912. Serial No. 711,118.

To all whom it may concern:

Be it known that I, ANDREW G. BRANDT, citizen of the United States, residing at Scranton, in the county of Lackawanna and 5 State of Pennsylvania, have invented certain new and useful Improvements in Milk-Bottles, of which the following is a specification.

This invention relates to sanitary milk 10 bottles of that type adapted to be destroyed after once being used, the principal object of the invention being to provide a receptacle of this character which can be cheaply manufactured, is durable in construction, 15 and which has means whereby the contents of the device can be viewed throughout the length of the receptacle.

With the foregoing and other objects in view which will appear as the description 20 proceeds, the invention resides in the combination and arrangement of parts and in the details of construction hereinafter described and claimed, it being understood that changes in the precise embodiment of the invention herein disclosed can be made within 25 the scope of what is claimed, without departing from the spirit of the invention.

In the accompanying drawings the preferred form of the invention has been shown. 30 In said drawings: Figure 1 is a side elevation of the bottle. Fig. 2 is a section on line A—B Fig. 1. Fig. 3 is a section through another portion of the bottle, the section being taken on the line E—F of Fig. 1. Fig. 4 is 35 an enlarged section through a portion of the bottom of the bottle. Fig. 5 is a perspective view of the cap or closure.

Referring to the figures by characters of reference 1 and 2 designate inner and outer 40 layers of stiff paper which are corrugated longitudinally and constitute the wall of the bottle, the longitudinal edges of these thicknesses being spaced apart, as shown in Fig. 3, so as to receive between them a narrow elongated strip 3 of celluloid or other 45 suitable transparent material. When the parts are assembled, it will be seen that an elongated tube is formed, the transparent strip constituting the joint whereby the tube 50 is completed. The corrugations in the paper thicknesses 1 and 2 can be compressed so as to give the tube any desired contour, and, as shown in Figs. 1 and 2, the upper portion of the tube can be reduced in diameter so as to 55 form a neck 4. This neck is reinforced by a metal ring 5 which fits snugly therein and

has its outer edge rolled outwardly as at 6 so as to grip the upper end of the bottle neck and thus not only hold said neck tightly against the ring 5 but also to hold the layers 60 1 and 2 and the upper end of the strip 3 properly assembled.

The bottom of the bottle is formed of a paper disk 7 having an annular flange 8, this disk being insertible into the lower portion 65 of the bottle and with its flange 8 extending downwardly. The lower edge of the wall of the bottle is then folded up under the disk 7 and against the inner surface of the flange 8 after which another or locking disk formed of paper and which is shown at 9 is inserted between the upturned portions of the bottle so as to clamp said portions firmly against the inner surface of the flange 8. This locking disk may also be 70 provided with an annular flange 10 whereby the clamping action of the disk upon the upturned portion of the bottle wall is increased. After the parts have thus been assembled the bottle is dipped in paraffin 75 or any other suitable water-proofing material, the transparent strip 3 being kept free of said material in any suitable manner. This water-proofing material will seal all joints as well as prevent the fibrous material 80 of which the bottle is made from absorbing any of the contents of the bottle.

The closure of the bottle is formed of a paper disk 11 having an annular flange 12 upstanding therefrom, this disk being 85 adapted to fit tightly within the ring 5. An ear 13 may be extended from the flange 12 so as to project above the bottle neck when the closure is in use. This ear can be easily 90 grasped so as to facilitate the removal of 95 the closure.

Importance is attached to the fact that the transparent strip 3 constitutes the connection between the opposed edges of the sheets of paper 1 and 2 constituting the wall 100 of the bottle. It is thus possible to extend the transparent strip throughout the height of the strip and it becomes unnecessary to cut an opening in the bottle to receive a transparent strip, as has been done heretofore. As the transparent strip 3 extends throughout the height of the bottle it will 105 be seen that the contents of the bottle can be viewed readily and it thus becomes possible to determine the amount of cream in the 110 bottle and whether or not any sediment is contained upon the bottom of the receptacle.

What is claimed is:—

1. A receptacle of the class described including inner and outer paper sheets corrugated longitudinally, an elongated transparent strip extending throughout the length of and interposed between the longitudinal edges of said sheets, said strip constituting the sole connection between the opposed edges of each sheet to form a tube, a bottom secured in one end portion of the tube, and a reinforcing ring secured to the other end of the tube.
- 10 2. A receptacle of the class described including inner and outer sheets of paper, an

elongated transparent strip constituting the sole connection between opposed edges of each sheet, the longitudinal edges of said strip being interposed between the sheets and secured thereto, said strip extending throughout the length of the sheets, and a bottom surrounded by said sheets and strip. 15 20

In testimony whereof I affix my signature in presence of two witnesses.

ANDREW G. BRANDT.
